SUPERVISORY MEANS FOR COMMUNI-
CATING CHANNELS

Simeon C. Leyland, Bloomfield, N. J., assignor to
Westinghouse Electric & Manufacturing Company,
East Pittsburgh, Pa., a corporation of
Pennsylvania

Application November 4, 1939, Serial No. 302,908

20 Claims. (Cl. 177—311)

My invention relates to the supervision of communicating channels, and particularly the supervision of a carrier-current channel such as is utilized for protecting transmission lines against faults, and for inter-station communication over the transmission line or system. My invention relates to the periodical checking of the condition of the carrier-current transmitters and receivers at each end of a protected line-section of a transmission line, particularly where carrier-current relaying is utilized.

An object of my invention is to provide automatic means, instigated automatically or by an operator, at only one end of the protected line-section, for obtaining a complete check-back, indicating whether the carrier-current transmitting and receiving equipments at both ends of the line-section are functioning properly and whether the line section is intact, and if not, indicating which equipment is at fault.

A still further object of my invention is to provide an automatic periodic check-back system for such carrier-current equipments, operative automatically at periodic intervals, and sounding an alarm-signal to indicate when the equipment at either one or both ends of the protected line-section is not operating properly.

With the foregoing and other objects in view, my invention consists in the apparatus, parts, combinations, methods and systems hereinafter described and claimed, and illustrated in the accompanying drawing wherein:

Figure 1 is a diagrammatic view of circuits and apparatus illustrating my invention in a preferred form of embodiment;

Fig. 2 is an "across the line" diagram of the supervisory equipment at a first station, M, of the line;

Fig. 3 is an "across the line" diagram of the supervisory equipment at a second station, N, of the line; and

Fig. 4 is an "across the line" diagram of a modified form of embodiment of the supervisory equipment for the first station, M'.

As shown in Fig. 1, my invention is illustrated as being applied to a carrier-current channel which is superimposed upon one phase-conductor of a 3-phase transmission line 5 which is illustrated as extending between two different stations designated M and N. The carrier-current channel is provided by means of a normally non-transmitting carrier-current transmitter 6 and a carrier-current receiver 7 at a first station, M, and a normally non-transmitting carrier-current transmitter 8 and a carrier-current receiver 9 at

a second station, N, all of said carrier-current apparatus being tuned to the same carrier-current frequency. The transmitter 6 and receiver 7 at the station M are coupled to the third phase-conductor of the line 5, through a coupling transformer 11 and a coupling capacitor 12 at the station M, while the transmitter 8 and receiver 9 at the station N are coupled to said third phase-conductor of the line 5 through a coupling transformer 13 and a coupling capacitor 14. Suitable wave-traps 15 and 16 are utilized for more or less confining the carrier currents to the portion of the line 5 extending between the two stations M and N.

The carrier-current equipment thus far described constitutes a communicating channel such as is utilized in protecting transmission lines against faults, an example of such a protective system being shown in the Harder Patent No. 2,144,493, granted January 17, 1939, and assigned to the Westinghouse Electric & Manufacturing Company.

While my invention, in its broadest aspects, is not limited to this particular kind of a communication channel, the invention was nevertheless particularly designed for such a carrier-current protective system, where the carrier-current channel is utilized primarily for protective purposes, to afford protection in the event of a fault, but usually also the communication channel is utilized, at times when there are no faults, for general communication-purposes between the operators at the two stations at the respective ends of the protected line-section, absolute control of the carrier-current channel being given to the protective equipment, in the rare moments when there is a fault on the transmission system, regardless of any other uses of the carrier-current channel.

My present invention relates to the supervision of such a carrier-current channel, to determine, at more or less frequent intervals, whether the carrier-current equipment is in proper condition for protecting the transmission line against faults, or for the normal purpose for which the carrier-current channel is utilized.

According to my invention, supervisory equipment is provided for causing the transmitter 6 at the first station, M, to begin to transmit carrier-current. This may be done in any one of a number of ways, the illustrated method of control being to connect the grid 17 of an oscillator-tube 18 to the cathode 19 of said tube, said cathode 19 being also connected, for grid-control purposes, to the positive terminal (+) of the station-

battery, the negative terminal of which is indicated at (—). The receiver 7 at the first station, M, is properly tuned to the carrier-current frequency, and is provided with an amplifier-tube or 5 output-tube 21 having a plate-circuit 22 which energizes a receiver relay RM from a B-battery which is represented by the terminals (B+) and (B—).

At the second station, N, the transmitter 8 is 10 also caused to transmit by connecting its oscillator-grid 17 to its oscillator-cathode 19, the latter being also connected, for grid-control purposes, to the positive terminal (+) of the station-battery. The receiver 9 at said second station, N, is utilized to energize a receiver relay RN which is energized from the B-battery at 15 this station.

The supervisory equipment at the first station, M, includes a long-interval timer TK and a 20 short-interval timer TM, which are, in reality, suitably geared synchronous motors energized from a 60-cycle source 24. At the second station, N, a short-interval timer TN is utilized, similarly energized from a 60-cycle source 25 at 25 that station. The 60-cycle sources 24 and 25 may, or may not, be tied in with the protected transmission-line 5. Each of the three timers TK, TM and TN is provided with an arm 26, which carries a plurality of moving contact-ele- 30 ments such as 27, said arm being normally biased, against a back-stop 28, by means of a returning-spring 29. When the timer is energized from its 60-cycle source, its contact-arm 26 moves slowly away from its back-stop 28, at a 35 speed which is determined by the speed of the timer-motor and the gear ratio which is utilized. When the timer is disconnected from its 60-cycle source, the construction is such that the return-spring 29 quickly returns the movable arm 26 to 40 its initial position against the back stop 28, this return-motion being effected in any convenient period of time, which will be assumed to be 0.1 second, for purposes of explaining the invention, although any other convenient resetting-time 45 may be utilized.

The long-interval timer TK has two contacts 50 TK50 and TK50', both of which close, in 50 minutes after the timer is energized, or after any other convenient time-interval.

50 The short-interval timer TM at the station M has four contacts as follows: contacts TMO, which close instantly, or within a short time after the timer is energized, and which open near the close of the check-back operation, which 55 may be in, say, 6 seconds after the timer is energized; normally closed contacts TM4, which open in 4 seconds after the timer is energized; normally open contacts TM4' which close in 4 seconds after the timer is energized, and which 60 thereafter remain closed as long as the timer is energized; and normally closed contacts TM5 which open in 5 seconds after the timer is energized.

At the second station, N, the short-interval 65 timer TN has three contacts, as follows: normally open contacts TN3 and TN3', both of which close in 3 seconds and remain closed during the rest of the energization of the timer; and normally closed contacts TN7, which open in 7 seconds after the energization of the timer, and which are utilized to finally terminate the supervisory or check-back operation, as will be subsequently described.

The relative orders of the short-term time- 75 settings of the timers TM and TN are signifi-

cant, although their absolute values are not, except that the shortest interval, here indicated as 3 seconds, should be longer than the longest carrier-current operation which is required in order to properly control the protective relaying 5 equipment (not shown), or other normal-use equipment of the carrier-current channel, it being understood that my present invention relates particularly to the supervisory or checking equipment, for assuring that the channel is in 10 constant readiness for its normal use, regardless of what that normal use may be.

The receiver relays RM and RN are of the instantaneous type. The relay RM has three normally open or "make" contacts RM1, RM2 and 15 RM3, which close when the relay is properly energized. The relay RN has two "make" contacts RN1 and RN2.

In addition to the foregoing equipment, the 20 illustrated form of embodiment of my supervisory apparatus embodies a push-button PBM at the first station, M, three bells or other signalling-means 1, 2 and 3, at the first station, M, and an auxiliary relay A and a resistor AR, at 25 the first station, M, the relay A being of the instantaneous type and having two "make" contacts A1 and A2. At the second station, N, the equipment further includes a push button PBN and a bell or other signalling-means 4.

The electrical connections of the equipment, 30 and the cycle of operations, are as follows.

The beginning of the long time-interval of 50 minutes, more or less, between successive automatic checking-operations of the supervisory equipment, is initiated by the deenergization of 35 the short-interval timer TM, which results in the reclosure of its contacts TM5. These contacts, when closed, connect the long-interval timer TK across the 60-cycle mains 24 at the station M. Fifty minutes later, the timer-contacts TK50 and TK50' close. The contact TK50 is connected, in series with the normally closed contact TM4, between the oscillator-grid 17 and the positive terminal (+) of the station-battery, and thence also to the oscillator-cathode 19. The 40 oscillator-tube 18 of the carrier-current transmitter 6 may be regarded as being of a type which does not oscillate when its grid 17 is disconnected from its cathode 19, or when it has a negative potential with respect to its cathode 19, but the 45 tube oscillates when the grid 17 has substantially the same potential as the cathode 19. The closure of the timer-contact TK50 thus initiates a supervisory transmission of carrier-current, from 50 the first station, M.

The second timer-contact TK50' is connected 55 in series with the short-interval timer TM, at the same station M, so as to initiate the operation of said short-term timer, which immediately, or soon, results in the closure of its first timer-contact TMO, which by-passes the timer-contact TK50', thus sealing in the short-interval timer TM until it has run its course, as determined by the opening of its sealing-in contact 60 TMO, 5 seconds later.

The initiation of the operation of the carrier-current transmitter at the first station, M, results in the instantaneous response of both the receiver 7 at the first station, M, and the receiver 9 at the second station, N, thus instantly energizing both of the receiver relays RM and RN, provided that both receivers 7 and 9 are in proper operating condition, and further provides that the transmitter 6 at the first station, M, is also in proper operating condition. The energiza- 70 75

tion of the two receiver relays RM and RN results in the immediate closure of the three relay-contacts RM1, RM2 and RM3 at the station M, and the two relay-contacts RN1 and RN2 at the station N.

At the station M, the receiver contact RM1 immediately short-circuits the operating coil of the auxiliary relay A, so that it will thereafter be impossible to effectively energize this auxiliary relay as long as the receiver relay RM remains properly energized. The receiver-relay contact RM2 is connected in series with the bell 2, and also in series with the normally open timer-contact TM4', so that the closure of the receiver-relay contact RM2 does not immediately result in the sounding of the bell 2. The receiver-relay contact RM3 instantly energizes the bell 3 across the station-battery which is represented by the positive and negative terminals (+) and (-). During an automatic supervisory check-back operation, if the carrier-current transmitter 6 and receiver 7 at the first station, M, are both operating properly, this bell 3 instantly sounds, at the beginning of each supervisory check-back, and it normally remains sounding for about 7.1 seconds, as will subsequently be described.

At the second station, N, the instantaneous closure of the receiver-relay contact RN1 results in the connection of the short-interval timer TN across the 60-cycle bus 25 at that station, the timer TN being also connected in series with its normally closed timer-contact TN7. The second contact, RN2, of the instantaneous receiver relay RN, operates to ring a bell 4 which is illustrated as being energized from the station-battery at the second station, N, as represented by the positive and negative terminals (+) and (-). The bell 4, at the second station, N, thus also begins to ring instantly, at the beginning of each automatic supervisory test of the carrier-current equipment, and it also continues to ring for 7.1 seconds, if the equipment is in proper operating order.

The supervisory operations thus far described have all taken place substantially instantaneously upon the closure of the two long-interval timer-contacts TK50 and TK50'. The long-interval timer-contact TK50, in series with the short-interval timer contact TM4 at the first station, M, jointly operates to connect the transmitter-grid 17 to the transmitter cathode 19, maintaining said carrier-current transmission as long as the grid 17 remains connected to the cathode 19. This connection is maintained for 4 seconds, or until the short-interval timer-contact TM4 opens, which thus causes a discontinuance of the transmission of carrier at the first station, M, 4 seconds after the carrier was started at that station.

Before this 4-second time-interval has elapsed, the timer TN, at the other station N, will have closed its contacts TN3 and TN3', which close in, say, 3 seconds. The timer-contact TN3, at the station N, connects the transmitter-grid 17 to the transmitter-cathode 19, at that station, thus initiating the operation of the carrier-current transmitter 8 at said station N. The timer-contact TN3', at said station N, by-passes the receiver 9 at that station, and seals in the receiver relay RN, thereafter maintaining the energization of said receiver relay across the B-battery terminals (B+) and (B-). This sealing-in of the receiver relay RN assures the maintenance of the receiver-relay contact RN1 until the timer TN has run its full course, as determined by the

timer-contact TN7 which opens in 7 seconds, thus finally deenergizing the timer TN and returning its timer-contacts to their initial or normal positions.

At the termination of the 4-second interval, the timer TM, at the first station, M, simultaneously opens its contact TM4 and closes its timer-contact TM4'. As previously described, the opening of the timer-contact TM4 interrupts carrier-current transmission at that station M. At the same time, or immediately thereafter, the closure of the timer-contact TM4' results in a completion of the energization of the bell 2, in series with the receiver-relay contact RM2, and across the station-battery terminals (+) and (-), provided, of course, that the transmitter 8 at the other station, N, and the receiver 7 at this station, M, are both operating properly. The ringing of the bell 2, four seconds after the beginning of the ringing of the bell 3, thus signifies that the check-back is complete, that is, that the carrier-current transmitter 6 and receiver 7 at the first station, M, are both operating properly, and that the carrier-current receiver 9 and transmitter 8 at the second station, N, are also operating properly. If everything is operating properly, this check-back bell 2 rings for, say, 2.1 seconds, or until immediately after the deenergization of the timer TM as a result of the opening of the timer-contact TM0, as will be subsequently described.

The timer-contact TM4', which closes at the end of the 4-second interval, also completes a circuit through the short-circuited coil of the auxiliary relay A and the resistor AR, across the battery-terminals (+) and (-), the coil of the auxiliary relay A being short-circuited by the receiver-relay contact RM1 if the receiver 7 at the station M is properly receiving carrier current which is transmitted from the transmitter 8 at the station N, at that time.

If the proper carrier-current signal is not received, at the close of this 4-second time-interval, the receiver-relay contact RM1 will not be closed, so that the closure of the timer-contact TM4' will instantly energize the auxiliary relay A, causing the latter to permanently seal itself in, through its relay-contact A1, and also to permanently connect the alarm-bell 1 across the station-battery, through its relay-contact A2, thus indicating that carrier current is not being received from the remote station N at the end of this 4-second time interval, at which time it should be received, if everything were in proper order. The silence of the bell 2, as a result of the open condition of the receiver-relay contact RN2, will also be an indication that the carrier-current equipment is not operating properly. Meanwhile, if the bell 3 has been ringing for the first 4 seconds, while the transmitter 6 at this station, M, was transmitting, said bell 3 will have indicated that the carrier-current equipment at this station, M, is operating correctly, so that the trouble must be at the other station, N.

At the end of the 5-second period after the initiation of the supervisory checking operation, the timer-contact TM5 opens, at the station M, thus deenergizing the long-interval timer TK, so that, in say, 0.1 second thereafter, or substantially instantaneously, the long-interval timer-contacts TK50 and TK50' will both reset, that is, will both return to their normal open positions. The opening of the timer-contact TK50 will interpose a second break in the grid-to-cathode circuit of the transmitter 6, so that the subsequent

reclosure of the short-interval timer-contact TM⁴ will not restart the carrier-current transmitter when the short-interval timer TM resets, about a second later. The opening of the timer-contact TK⁵⁰' makes it possible for the parallel-connected timer-contact TMO to subsequently deenergize the short-interval timer TM.

At the end of the 6-second interval after the initiation of the above-described supervisory check, the timer-contact TMO opens, deenergizing the short-interval timer TM at the station M. Within a very short-interval, such as 0.1 second, thereafter, the timer-contact TM⁵ recloses, restarting the 50-minute timer TK. At the same time, the timer-contact TM⁴' reopens, silencing the check-back bell 2, and the timer-contact TM⁴ recloses, making it possible for the long-interval timer-contact TK⁵⁰ to subsequently restart the carrier-current transmission at said station M, at the end of another 50-minute interval.

At the end of the 7-second interval after the first initiation of carrier-current transmission, sustained for at least three seconds, at the first station, M, the timer TN at the second station, N, finally opens its contact TN¹, thus deenergizing said timer TN. Within a short time, such as 0.1 second, thereafter, the timer-contacts TN³ and TN³' reset, or reopen, the former stopping carrier-current transmission at said station N, and the latter removing the holding-circuit from the receiver relay RN, thus permitting said receiver relay to become deenergized simultaneously with the cessation of carrier-current transmission. The receiver-relay contact RN¹ reopens, thus preventing the timer TN from becoming reenergized when the timer-contact TN¹ returns to its normal closed position. At the same time, the receiver-relay contact RN² opens, silencing the bell 4 at said station N. Upon the interruption of carrier-current transmission at the station N, the receiver relay RM is also de-energized at the station M, thus silencing the bell 3.

If the carrier-current equipment is operating properly, the bells 3 and 4 will both begin ringing instantaneously at the beginning of each check-back test, and they will remain ringing for approximately 7.1 seconds, while the bell 2 will remain silent for 4 seconds and will then ring for approximately 2.1 seconds, and the bell 1 will not ring at all. If the carrier-current transmitter 6 at the first station, M, is not operating properly, the bells 2, 3 and 4 will all remain silent, and the alarm-bell 1 will begin ringing at the end of the 4-second interval, and will continue thereafter to ring until the station-attendant shuts it off. If the carrier-current receiver 7 at the first station, M, is incapable of receiving carrier-current transmitted from its own station M, the bells 2 and 3 will not ring at all, at this station, but the bell 4 will ring at the other station, N, and the alarm-bell 1 will start ringing, as before, at the end of the 4-second interval. If the receiver 7 at the station M can receive from its own transmitter 6, but not from the transmitter 8 at the other station N, either through a fault of the receiver 7, or from a failure of the carrier-current equipment at the other station, N, the bell 3 will ring for 3 seconds, instead of 7.1 seconds, the bell 2 will not ring at all, and the alarm-bell 1 will ring as previously described.

The foregoing operations thus afford a complete check-up on the carrier-current equipment at both ends of the transmission-line 5, as well

as a check-up on the line itself, so that the attendant at the station M will hear the alarm-bell 1 if anything is wrong with the carrier-current equipment at either end of the line.

The 3-second time-interval which is provided by the timer TN at the second station, N, makes it necessary for the carrier-current to be continuously transmitted, from the first station, M, for 3 seconds, before the check-back operation is assured, thus making it possible to utilize the carrier-current equipment in any manner which does not result in uninterrupted carrier-current transmission, from both ends combined, for an uninterrupted time as long as 3 seconds, without instigating a check-back supervisory initiation of carrier-current transmission at the second station, N. Thus, normal fault-responsive relaying operations will always be completed in much less than the 3-second interval which is provided.

Furthermore, the 3-second interval also makes it possible to signal from one end of the transmission line 5, to the other, by means of the respective push buttons PBM and PBN. These push buttons are utilized to connect the respective oscillator-grids 17 to their respective cathodes 19, so as to start carrier-current transmission at the corresponding end of the transmission-line 5. Each time carrier-current transmission is started by pressing either push button PBM or PBN, the bells 3 and 4 are rung, in both stations, and these bells may be sounded, in codes of two or more rings, to call the attention of the operator at the other station, either as a telephone-bell to ask him to answer the telephone, or for any other purpose, provided that the call-code does not involve a continuous depression of either push button PBM or PBN for as long as 3 seconds at any one time.

While I have just described my invention in connection with a complete automatic equipment, which automatically instigates a rechecking supervisory operation at the end of each 50-minute time-interval, or any other interval as controlled by the long-interval timer TK, it will be obvious that I am not limited to this complete equipment, in each case.

Thus, as indicated in Fig. 4, the long-interval timer TK can be dispensed with entirely, and its contact TK⁵⁰, which initiates the supervisory carrier-current transmission at the station M, can be replaced by a push-button control. In Fig. 4, a push button PB is utilized to energize an auxiliary relay B having two instantaneous "make" contacts B1 and B2. The contact B1 initiates carrier-current transmission, at its own station M', preferably, though not necessarily, in series with a timer-contact T⁴ corresponding to the timer-contact TM⁴ of Figs. 1 and 2, while the contact B2 energizes the timer T which corresponds to the timer TM of Figs. 1 and 2. The timer T has only the normally closed contact T⁴, which opens in 4 seconds, and the normally open contact T⁴' which closes in 4 seconds, the latter contact corresponding to the contact TM⁴' of Figs. 1 and 2. The receiver relay RM and the auxiliary relay A are connected and utilized, in Fig. 4, in the same manner as in the preferred or complete form of embodiment of my invention, as shown in Figs. 1 and 2.

In operation, in order to obtain a supervisory carrier-current check-back, with the equipment at the station M', as shown in Fig. 4, and with the same equipment, at the other station, N, as is shown in Figs. 1 and 3, the push button PB is depressed at the station M', and is held down

for at least 3 seconds, until the transmitter 8 at the other station, N, begins to transmit. As a matter of practical operation, the push button PB may be held down until the check-back bell 5 2 rings, at the close of the 4-second interval, at which time the push button PB should be released, so that it will be released at least before the station N transmitter 8 stops transmitting at the end of the 7-second interval. The operation of the equipment shown in Fig. 4 is otherwise the same as was described for Figs. 1, 2 and 3, except that the operator at the station M' must initiate each supervisory check-back operation, instead of having the long-interval timer 10 15 TK to perform this service for him.

While I have illustrated my invention in two forms of embodiment which are at present preferred by me, it will be obvious that I am not limited to all of the details of apparatus or function which have been specifically described, and I desire my description and illustration to be understood in an illustrative sense, illustrating the general principles of my invention, rather than to be taken in a restrictive sense as limiting my invention to the precise details or processes shown. I desire, therefore, that the appended claims shall be accorded the broadest construction consistent with their language and the prior art.

30 I claim as my invention:

1. In a carrier-current system comprising a normally non-transmitting carrier-current transmitter and a carrier-current receiver at a first station, and a normally non-transmitting carrier-current transmitter and a carrier-current receiver at a second station in communicable relation to said first station, all of said carrier-current apparatus being operative at the same carrier-current frequency, the combination, with 35 40 45 50 55 60 65 70 75 said system, of supervisory equipment comprising supervisory means for causing a supervisory carrier-current transmission at the first station, supervisory time-delay means responsive to a continued receipt of carrier for a first predetermined time at the second station for thereupon initiating a supervisory carrier-current transmission at said second station and for maintaining said supervisory carrier-current transmission for a second predetermined time, supervisory time-delay means for facilitating the interruption of said supervisory carrier-current transmission at the first station after a third predetermined time after the initiation of said supervisory carrier-current transmission, said third predetermined time being longer than said first predetermined time but shorter than the sum of said first and second predetermined times, and indicating means responsive, in any predetermined manner, to the various operations of said first and second stations, respectively.

2. In a carrier-current system comprising a normally non-transmitting carrier-current transmitter and a carrier-current receiver at a first station, and a normally non-transmitting carrier-current transmitter and a carrier-current receiver at a second station in communicable relation to said first station, all of said carrier-current apparatus being operative at the same carrier-current frequency, the combination, with 65 70 75 80 85 90 95 100 said system, of supervisory equipment comprising supervisory means for causing a supervisory carrier-current transmission at the first station, supervisory time-delay means responsive to a continued receipt of carrier for a first predetermined time at the second station for there-

upon initiating a supervisory carrier-current transmission at said second station and for maintaining said supervisory carrier-current transmission for a second predetermined time, supervisory time-delay means for facilitating the interruption of said supervisory carrier-current transmission at the first station after a third predetermined time after the initiation of said supervisory carrier-current transmission, said third predetermined time being longer than said first predetermined time but shorter than the sum of said first and second predetermined times, and indicating means responsive to a non-receipt of a predetermined carrier current by the receiver at the first station after said interruption of said supervisory carrier-current transmission at said first station.

3. In combination, means for transmitting a signal at a first station and for receiving it both at said first station and at a second station, 20 means responsive to a continued receipt of said signal for a first predetermined time at said second station for thereupon sending a continued signal, for a second predetermined time, to the first station and for receiving the last-mentioned signal at said first station, time-delay means for facilitating the interruption of said signal-transmission at said first station after a third predetermined time after the initiation of said signal-transmission, said third predetermined time being longer than said first predetermined time but shorter than the sum of said first and second predetermined times, and indicating means responsive to a non-receipt of a signal at said first station after said interruption of said signal-transmission at said first station.

4. In combination, means for transmitting a signal at a first station and for receiving it at a second station, means responsive to a continued receipt of said signal for a first predetermined time at said second station for thereupon sending a continued signal, for a second predetermined time, to the first station and for receiving the last-mentioned signal at said first station, time-delay means for facilitating the interruption of said signal-transmission at said first station after a third predetermined time after the initiation of said signal-transmission, said third predetermined time being longer than said first predetermined time but shorter than the sum of said first and second predetermined times, and indicating means responsive to a non-receipt of a signal at said first station after said interruption of said signal-transmission at said first station.

5. In a carrier-current system comprising a normally non-transmitting carrier-current transmitter and a carrier-current receiver at a first station, and a normally non-transmitting carrier-current transmitter and a carrier-current receiver at a second station in communicable relation to said first station, all of said carrier-current apparatus being operative at the same carrier-current frequency, the combination, with said system, of supervisory equipment comprising supervisory means for causing a supervisory carrier-current transmission at the first station, supervisory time-delay means responsive to a continued receipt of carrier for a first predetermined time at the second station for thereupon initiating a supervisory carrier-current transmission at said second station and for maintaining said supervisory carrier-current transmission for a second predetermined time, supervisory time-delay means for providing

- an indication of the receipt of a predetermined carrier current by the receiver at the first station after a third predetermined time after the initiation of the supervisory carrier-current transmission at said first station, said third predetermined time being longer than said first predetermined time but shorter than the sum of said first and second predetermined times.
6. In combination, means for transmitting a signal at a first station and for receiving it both at said first station and at a second station, means responsive to a continued receipt of said signal for a first predetermined time at said second station for thereupon sending a continued signal, for a second predetermined time, to the first station and for receiving the last-mentioned signal at said first station, and time-delay means for providing an indication of the receipt of a signal at the first station after a third predetermined time after the initiation of said signal-transmission at said first station, said third predetermined time being longer than said first predetermined time but shorter than the sum of said first and second predetermined times.
7. In combination, means for transmitting a signal at a first station and for receiving it at a second station, means responsive to a continued receipt of said signal for a first predetermined time at said second station for thereupon sending a continued signal, for a second predetermined time, to the first station and for receiving the last-mentioned signal at said first station, and time-delay means for providing an indication of the receipt of a signal at the first station after a third predetermined time after the initiation of said signal-transmission at said first station, said third predetermined time being longer than said first predetermined time but shorter than the sum of said first and second predetermined times.
8. The invention as defined in claim 2, in combination with supervisory time-delay means for providing an indication of the receipt of a predetermined carrier current by the receiver at the first station after said third predetermined time.
9. The invention as defined in claim 3, in combination with time-delay means for providing an indication of the receipt of a signal at the first station after said third predetermined time.

10. The invention as defined in claim 4, in combination with time-delay means for providing an indication of the receipt of a signal at the first station after said third predetermined time.

11. The invention as defined in claim 2, in combination with quickly operating means for responding to the receipt of a predetermined carrier current by the receiver at at least one of said stations.

12. The invention as defined in claim 3, in combination with quickly operating means for responding to the receipt of a signal at at least one of said stations.

13. The invention as defined in claim 4, in combination with quickly operating means for responding to the receipt of a signal at at least one of said stations.

14. The invention as defined in claim 5, in combination with quickly operating means for responding to the receipt of a predetermined carrier current by the receiver at at least one of said stations.

15. The invention as defined in claim 6, in combination with quickly operating means for responding to the receipt of a signal at at least one of said stations.

16. The invention as defined in claim 7, in combination with quickly operating means for responding to the receipt of a signal at at least one of said stations.

17. The invention as defined in claim 1, in combination with means for automatically initiating the supervisory carrier-current transmission at the first station at long predetermined intervals.

18. The invention as defined in claim 4, in combination with means for automatically initiating the signal-transmission at the first station at long predetermined intervals.

19. The invention as defined in claim 5, in combination with means for automatically initiating the supervisory carrier-current transmission at the first station at long predetermined intervals.

20. The invention as defined in claim 7, in combination with means for automatically initiating the signal-transmission at the first station at long predetermined intervals.

SIMEON C. LEYLAND.
